UNITED STATES PATENT OFFICE

121,150

DESIGN FOR A RIBBON FABRIC OR SIMILAR ARTICLE

Jacob Schnitt, New York, N. Y., assignor to Gershon Amster, Brooklyn, N. Y.

Application April 29, 1940, Serial No. 92,009

Term of patent 7 years

To all whom it may concern:

Be it known that I, Jacob Schnitt, a citizen of the United States, residing at New York city, in the county of New York and State of New York, have invented a new, original, and ornamental Design for a Ribbon Fabric or Similar Article, of which the following is a specification, reference being had to the accompanying drawing, forming part thereof.

The figure of the drawing is a plan view of the ribbon fabric showing my design.

I claim:

The ornamental design for a ribbon fabric or similar article, substantially as shown.

JACOB SCHNITT.
